United States Patent

Des. 242,318

Patented Nov. 16, 1976

242,318

STAND FOR POTTED PLANTS

Ismael Gomberoff and Patricio Uribe, both of 6965
Guide Meridian Ave., Lynden, Wash. 98264

Filed Nov. 10, 1975, Ser. No. 630,450

Term of patent 14 years

Int. Cl. D6—04

U.S. Cl. D6—183

FIG. 1 is an isometric view of a stand for potted plants showing our new design;

FIG. 2 is a front elevational view thereof;

FIG. 3 is a rear elevational view thereof;

FIG. 4 is a top plan view thereof; and

FIG. 5 is a bottom plan view thereof.

I claim:

The ornamental design for a stand for potted plants, substantially as shown and described.
